United States Patent Office

Des. 216,009
Patented Nov. 18, 1969

216,009

RESTAURANT BUILDING

Domenico Spano, Long Beach, Calif., assignor to
Domenico's Gondola, Inc., Long Beach, Calif., a
corporation of California

Filed Mar. 24, 1969, Ser. No. 16,396

Term of patent 14 years

Int. Cl. D25—04

U.S. Cl. D13—1

Fig. 4.

Fig. 5.

FIG. 1 is a three-quarter front perspective view of a restaurant building showing my new design;

FIG. 2 is a top plan view of said building;

FIG. 3 is a side elevational view of the side of the building opposite that shown in FIG. 1.

FIG. 4 is an end view of said building; and

FIG. 5 is an end view of the end of said building opposite FIG. 4.

I claim:

The ornamental design for a restaurant building, substantially as shown and described.
